BOWLING PIN PICKUP APPARATUS

George A. Montooth and Albert M. Bowen, Long Beach, Calif., assignors to The Brunswick-Balke-Collender Company

Original application March 26, 1946, Serial No. 657,238, now Patent No. 2,697,605, dated December 21, 1954. 10 Divided and this application February 7, 1952, Serial No. 270,371

9 Claims. (Cl. 273—43)

This invention relates to machines for setting pins on 15 bowling alleys and more particularly to an automatic pin handling mechanism.

This application is a division of applicants' prior application, Serial Number 657,238, filed March 26, 1946, now Patent No. 2,697,605.

The present invention has for its primary object to provide a pin lifter mechanism which is automatic in operation and which will function properly regardless of pin location.

Another object of the invention is to provide a pin lifter or pick-up mechanism which is self-latching. The operation is such that the lifter engages the pins, which are automatically latched and held in engaged relation.

Another object of the invention is to provide a pick-up mechanism having a self-latching device which will release itself without any external control and solely by relative movement between parts of the pick-up mechanism.

Another object of the invention is to provide a pin lifter mechanism having parallel bars which may be moved out of the playing area quickly and to a position where contact with a thrown ball or flying pins will not occur.

In the drawings, like reference characters designate similar parts in the several views.

Figure 1 is a vertical sectional view of a pin setting mechanism according to the present invention.

Figure 2 is a detailed vertical sectional view of one of ten similar pin engaging units of a pin-setting rack used in the invention.

Figure 3 is a sectional view thereof as seen at right angles to Figure 2.

Figure 4 is a broken plan view thereof.

Figure 5 is a fragmentary view thereof, as seen along the line 5—5 of Figure 3.

Figure 6 is a further broken view of parts shown in Figure 5 in another position.

Figure 7 shows a group of four vertical sectional views of a latch used in the invention and in various positions thereof.

The alley 100, its pin-spotting deck 101 and its gutters are conventional, the alley terminating in a pit 103 provided with a back-stop 104 for receiving the impact of the ball and any pins which may be propelled against it. The pit 103 is provided with means 105 for lifting a ball from a low point in the pit to an elevated point from which it is discharged for return or delivery to the bowler, with means 106 initiating the synchronous movement of various portions of the mechanism, and means 107 for moving pins in the pit for elevation therefrom by a lift conveyor 108. The latter serves to move the pins to an elevated point of the mechanism for discharge into a chute 109. A pin magazine 110 receives the pins from the chute 109 and, when filled with a full complement of ten pins, discharges them into a pin tray 111 therebeneath having cans arranged to receive and hold the pins in the arrangement they will have when placed on

2

the alley deck. Said tray is movable to a position over the deck 101 for extraction of the pins therefrom by a pin setting rack 112. The rack not only serves to receive a full complement of pins from the tray 111 and deposit them in proper spotted position on the deck 101 but also serves to engage and lift any pins left standing after a ball has been rolled so that said deck can be swept clear of fallen pins. The rack re-deposits such pins in the same positions from which they have been lifted subsequent to clearing the deck so that they are ready for the second ball to be rolled.

The mechanism further includes a guard 113 which has a normal elevated position and is moved to a position across the alley in front of the deck during the period of operation of the mechanism to protect the same against injury by a prematurely rolled ball. A squeegee or deck clearing device 114 moves vertically with the guard and also moves rearwardly to sweep the deck of fallen pins after the pin setting rack has lifted standing pins. There is also provided a pin deck cover 115 suitably elevated with respect to the deck 101 to give ample pin clearance. Said cover 115 is normally closed to protect the rack 112 and other mechanism from injury by flying pins but opens synchronously with the downward movement of the guard 113 so that the rack 112 may move vertically through the resulting opening.

The mechanism also provides means for receiving a ball from the lift 105 for return thereof to the bowler.

Pin spotting carriage or rack 112

This device is best illustrated in Figures 1 to 7. As seen in Figure 1, the rack (which may also be referred to as a carriage) is raised and lowered by a pressure fluid cylinder 264 which receives fluid under pressure for two-way or up and down motion of the rack, from the pump 243. Figure 1 shows a four-way valve 265 for controlling the operation of the piston rod 266 of the cylinder and, because of the latter's connection with the rack, the raising and lowering of said rack. This valve may be controlled manually or by the mechanism shown in applicants' parent application.

The rack comprises a relatively large fabricated frame 266 of generally triangular shape. Because of its size, said frame is apt to be distorted by pressure forces as applied by the cylinder 264. Accordingly, means are provided for maintaining all portions of the frame, and the three corners thereof, level at all times. Said means comprise upstanding brackets 267 fixed on the frame at the corners thereof, a transverse shaft 268, and a longitudinal shaft 269 connected by bevel gearing, not shown. Pinion gears 271 on the outer ends of shafts 268 and 269 are arranged to mesh with vertical gear racks 272 carried fixedly by the framing of the machine. Except for negligible torsion of the shafts 268 and 269, the engagement of the gears with their respective racks will maintain the rack frame 266 level at all times. The frame also carries rollers 273 which engage the smooth sides of the racks to further stabilize the structure. The weight of the rack is counter-balanced by a counter-weight 274 which is connected by a cable 275, trained over pulleys 276, to a mid-point of the rack frame 266.

The frame 266 is provided with ten similar pin grasping and lifting units 277 arranged in the same pattern as are the cans of the pin tray 111.

Each unit comprises inter-dependent mechanisms consisting of a vertically movable mechanism 278 and a horizontally movable pin lifting and holding carriage 279.

The mechanism 278 includes a horizontal plate 280 provided on its underside with a compressible pad 281 and carried by a stem 282 slidably mounted in guide

ment relative thereto when the carriage is in a lowered position, means connecting said plate to said pin gripping bars operable to pivot the bars towards each other to grip a pin when the plate engages the top of a pin and is moved relatively to the carriage thereby, and automatically operated latch means operable to lock said bars in engaged relation with a pin, said latch means comprising a latch device carried by said plate and having a lug engaging the carriage as the plate is moved to an extreme position during the pin gripping operation, and means operable upon relative movement between the latch device and carriage when the carriage is moved to respot the pin on the pin deck and said plate is again moved to an extreme position by the pin for swinging said latch device to a disengaged position.

2. A pin handling apparatus, comprising a vertically movable carriage, a pin engaging plate having a guideway slidably mounted on the carriage, parallel pin-gripping bars carried by arms pivotally mounted on and depending from the carriage when a pin is gripped, and means for holding said bars in engagement with a pin including a push bar slidably mounted on the carriage having an end slidably mounted in said guideway to permit movement of the push bar relative to the plate, and links connecting the push bar and arms, said push bar upon movement in one direction relative to the carriage acting upon the links to swing the parallel bars outwardly and upwardly away from the position in which a pin is gripped.

3. A pin handling mechanism comprising a vertically movable carriage having spaced annular bearings, a pin engaging plate having a tubular extension mounted for sliding movement in said bearings, said extension having a slot therein extending in a direction transverse to the direction of sliding movement, spring means urging said plate downwardly into pin engaging position, pin engaging parallel bars pivotally mounted on the carriage for movement in an arcuate path to pin engaging position, means for moving the carriage, link means for swinging said parallel bars when said plate engages a pin thereunder and the carriage continues to move downwardly and latching means carried by the extension and normally disposed at a point below the bearings including a latch body portion having a pivot pin mounted in said slot, a latch lug on said body portion positioned to allow free passage of the lower bearing on its downward movement and operable to engage the lower of said spaced annular bearings after said free passage to maintain said parallel bars in pin engaging position and in so doing to shift the pivot pin to one end of the slot, an over-center spring for release of said engagement upon subsequent downward relative movement of the lower bearing with respect to the plate when the pin is resotted, and a throw lug on said body portion positioned for engagement by the lower bearing when the carriage is raised to a non-operative position to shift the pivot pin to the other end of said slot which shifts the spring and thus restores the latch to latching position.

4. A bowling pin lift mechanism having in combination a carriage, means for supporting the carriage above the pin deck of an alley for movement towards and from said deck, a pair of parallel pin gripping bars supported on said carriage for movement laterally thereof and for movement pivotally toward and from each other, a pin engaging plate slidably mounted on the carriage for movement therewith and for vertical movement relative thereto when the carriage is in a lowered position, means connecting said plate to said pin gripping bars operable to pivot the bars towards each other to grip a pin when the plate engages the top of a pin and is moved relatively to the carriage thereby, and automatically operated latch means carried by said plate and operable to lock said bars in engaged relation with a pin, said latch means comprising a latch device having a pivot having an initial position and movable to another position, a lug engaging the carriage as the plate is

10 moved to an extreme position during the pin gripping operation, said engagement causing a shifting of the pivot from the initial position to the other position, over-center spring means for swinging said latch device to a disengaged position when the carriage is moved to respot the pin on the pin deck and said plate is again moved to an extreme position by the pin, and means for shifting the pivot back to the initial position when the carriage is raised to an inoperative position above the deck and thus with the over-center spring means restoring the latch device to latching position.

15 5. A bowling pin lifting mechanism having, in combination, a carriage, means supporting the carriage above the pin deck of an alley for movement toward and away from said deck, a plurality of pin gripping members supported on said carriage for movement between withdrawn positions and pin engaging positions, a pin engaging plate slidably mounted on the carriage for movement therewith and for vertical movement relative thereto by engagement with the top of a pin, means connecting said plate to said pin gripping members operable to move the members to pin engaging positions when the plate engages the top of a pin and is moved relatively to the carriage thereby, and automatically-operated latch means operable to lock said members in engaged relation with a pin, said latch means comprising a latch device carried by said plate and having a lug engaging the carriage as the plate is moved to an extreme position during the pin gripping operation, and means operable upon relative movement between the latch device and carriage when the carriage is moved to respot the pin on the pin deck and said plate is again moved to an extreme position by the pin for swinging said latch device to a disengaged position.

20 30 35 40 45 50 55 60 65 70 75 7. A bowling pin lifting mechanism having, in combination, a carriage device, means for supporting the carriage device above the pin deck of an alley for movement towards and from said deck, a plurality of pin gripping members supported on said carriage device for movement between pin engaging positions and withdrawn positions, a pin engaging plate device slidably mounted on the carriage device for movement therewith and for vertical movement relative thereto, means connecting said plate device to said pin gripping members operable to move the members to pin engaging positions when the plate device engages the top of a pin and is moved relatively to the carriage device thereby, and automatically operated latch means operable to lock said members in engaged relation with a pin, said latch means comprising a latch member having a lug for latching the plate device and carriage device together, said latch member being mounted on one of said devices and positioned so that the lug may engage the other device as the plate device is moved to an extreme position during the pin gripping operation, and means operable upon relative movement between the latch member and carriage device when the carriage device is moved to respot the pin on the pin deck and said plate device is again moved to an extreme position by the pin for swinging said latch member to a disengaged position.

7. A bowling pin lifting mechanism having, in combination, a carriage, means for supporting the carriage above the pin deck of an alley for movement towards and from said deck, a plurality of sets of pin gripping members supported on said carriage for movement between withdrawn and pin engaging positions, a plurality of pin engaging plates slidably mounted on the carriage for movement therewith and for vertical movement relative thereto, there being a plate associated with each set of pin gripping members, means connecting each plate to its associated pin gripping members to move the members towards each other to grip a pin when the plate engages the top of a pin and is moved relatively to the carriage thereby, and automatically operated latch means operable to lock said members in engaged relation with a pin, said latch means comprising a latch device carried by
